UNITED STATES PATENT OFFICE.

JUICHI IKEDA AND MASASHI MIURA, OF KOBE, JAPAN.

TWOFOLD ENVELOPE OR DOUBLE ENVELOPE.

1,421,240.

Specification of Letters Patent. Patented June 27, 1922.

Application filed February 12, 1918, Serial No. 216,764. Renewed March 8, 1922. Serial No. 542,163.

To all whom it may concern:

Be it known that we, JUICHI IKEDA and MASASHI MIURA, subjects of the Emperor of Japan, and residents of Kobe, Empire 5 of Japan, have jointly invented a new and useful Two-Fold Envelope or Double Envelope, of which the following is a specification.

This invention has for its object to provide an improved envelope in which there is provided two chambers or compartments for the reception of enclosures, each compartment or chamber being provided with the separate sealing flaps thus permitting 10 the mouth of one compartment to be closed and sealed prior to the closure of the mouth of the other compartment.

Another object is the provision of a double envelope of this type in which the open 20 mouths of the respective compartments or chambers are disposed in contiguous relation and the sealing flaps therefor are correspondingly disposed for convenience in manipulation.

With these and other objects in view as will appear as the description proceeds the invention comprises the novel features of construction combination of elements and arrangement of parts which will be more 25 fully described in the following specification and set forth with particularity in the claim appended hereto.

Figure 1 represents a plan view of the blank from which the improved envelope 30 is constructed.

Figures 2 to 6 represent plan views of the envelope showing the various stages in the formation thereof, and,

Figure 7 represents a top plan view of 40 the completed envelope sealed.

Referring to the drawing in detail, wherein similar reference characters designate corresponding parts throughout the several views the letters D and I indicate the front 45 and intermediate or partition pieces, respectively. The intermediate piece I is provided with opposed side flaps H and J and the front piece D is provided with laterally opposed wide flaps E and C. The flaps E and J and the flaps C and H at the opposed 50 sides of the front and intermediate pieces are divided by substantially V-shaped slits defining substantial triangular reinforcing pieces F and G and the outer terminals of 55 the side flaps H and J are provided with the supplementary sealing flap sections K.

The terminal of the piece D opposite the intermediate piece I is provided with a main sealing flap B and disposed adjacent thereto is the relatively narrow sealing tab A which 60 is carried by the terminal of one of the back flaps E.

The several parts of the envelope are designed to be folded along the lines indicated by dotted lines in Figures 1 to 3 and 65 the several parts are preferably folded to form the completed envelope in the following order. First the reinforcements F and G are folded inwardly across the line of fold between the pieces D and I so as to reinforce 70 the envelope structure at this point and the side flaps H and J are subsequently folded upon the intermediate piece I, said flaps H and J being of such width that the longitudinal edges thereof lie in overlapping relation and are secured together by a suitable adhesive composition so as to provide 75 an envelope or compartment. The intermediate piece I and side flaps H and J which have been folded thereon are subsequently 80 folded against the inner surface of the piece D along the line represented by the dotted line intersecting the longitudinal axes of the triangular reinforcing members F and G. The back flaps E and C are subsequently 85 folded upon the intermediate piece I and the flaps are secured together along their overlapped edges and are also preferably secured to the intermediate piece I at the portions remote from the flaps K and B 90 in order that the latter may be inserted under the unsecured portions of the back flaps C and E and between the latter and the intermediate piece I, subsequent to the insertion 95 of such material as it is desired to enclose within the several compartments or chambers of the envelope. Prior to sealing the flaps K and B access may be readily had to the compartments or chambers defined between the front piece D and the flaps H and J and between the flaps H and J and the intermediate piece I, the mouths of the respective compartments or chambers being disposed in contiguous relation as are also the sealing flaps B and K. Subsequent to insertion 100 of the several sealing flaps the sealing tab A is folded so as to overlie the front face of the front piece D, as shown in Figure 7 and the envelope is sealed so as to prevent tampering with the contents thereof by unauthorized persons by securing the tab A either directly to the front piece D or by a

110

postage stamp or other seal applied to the tab and front face of the piece D.

We claim:

- In a blank for a double envelope comprising a front piece, a piece connected therewith forming an intermediate partition when folded, side flaps carried by the front and partition pieces, the side flaps of the partition piece being foldable thereon, spaced supplemental closure flaps carried by the lower free edges of the side flaps of the said partition, triangular, overlapping reinforcing side portions between the flaps of the front and intermediate pieces, a main closure flap carried by the free edge of the front piece, the partition piece being foldable to dispose the side flaps thereof against the inner face of the front piece, the flaps of the partition piece dividing the interior

of the envelope into two chambers, said main and supplemental closure flaps being disposed in overlapping relation and the open mouths of the two chambers being disposed in contiguous relation, the side flaps of the front piece being foldable upon the partition piece and the main and supplemental closure flaps being adapted for insertion between the partition piece and the side flaps of the front piece, and a sealing tab carried by the upper free edge of one of the side flaps of the front piece adapted to be folded across the closure flaps and upon the front face piece to prevent opening of the main and supplementary closure flaps.

In testimony whereof we affix our signatures hereto.

JUICHI IKEDA.
MASASHI MIURA.
